CLAIM

The ornamental design for a debit card package assembly, as shown and described.

DESCRIPTION

FIG. 1 is a perspective view of the debit card package assembly;

FIG. 2 is a right side elevational view of the package assembly shown in FIG. 1, the left side elevational view being a mirror image thereof;

FIG. 3 is an front end elevational view of the package assembly shown in FIG. 1, the rear end elevational view being a mirror image thereof;

FIG. 4 is a top plan view of the package assembly shown in FIG. 1; and,

FIG. 5 is a bottom plan view of the package assembly shown in FIG. 1.

The broken line showing of a card is for illustrative purpose only and forms no part of the claim.

1 Claim, 2 Drawing Sheets

FIG. 4

FIG. 5
